UNITED STATES PATENT OFFICE

100,385

DESIGN FOR A COMBINATION DISPENSING NOZZLE AND METER

Jacob C. Miller, Milwaukee, Wis., assignor to
Badger Meter Manufacturing Company, Mil-
waukee, Wis., a corporation of Wisconsin

Application November 16, 1935, Serial No. 59,619

Term of patent 14 years

To all whom it may concern:

Be it known that I, Jacob C. Miller, a citizen of the United States, residing at Milwaukee, in the county of Milwaukee and State of Wisconsin, have invented a new, original, and ornamental Design for a Combination Dispensing Nozzle and Meter, of which the following is a specification, reference being had to the accompanying drawing, forming part thereof.

In the drawing:

Fig. 1 is a view in perspective of a combination dispensing nozzle and meter showing my new design.

Fig. 2 is a top plan view of the device shown in Fig. 1.

I claim:

The ornamental design for a combination dispensing nozzle and meter as shown.

JACOB C. MILLER.
